UNITED STATES PATENT OFFICE.

WILLIAM A. GWYNN, OF ST. LOUIS, MISSOURI, ASSIGNOR TO SUSIE E. GWYNN, OF ST. LOUIS, MISSOURI.

VULCANIZING MACHINE.

Application filed April 14, 1922. Serial No. 552,580.

To all whom it may concern:

Be it known that I, WILLIAM A. GWYNN, a citizen of the United States, residing in the city of St. Louis and State of Missouri, have invented new and useful Improvements in Vulcanizing Machines, of which the following is a specification.

This invention relates to vulcanizing machines of the type shown in my pending application, Ser. No. 421,816, filed November 5th, 1920.

The present invention embodies a novel construction of vulcanizing chamber shown but not claimed in the said pending application; the invention is further directed to novel means for securing the said vulcanizing chamber in position in the casing; and finally, another feature of the invention relates to novel means for securing the electric heater in position on the bottom of the vulcanizing chamber.

The invention is illustrated in the accompanying drawing in which—

Figure 1 is a top plan view of a vulcanizing machine such as shown in my application above referred to;

Figure 2 is a cross-sectional view on line 2—2 of Figure 1, taken through the insulating chamber and surrounding casing, and omitting the clamping mechanism shown in Figure 1;

Figure 3 is a longitudinal sectional view on the line 3—3 of Figure 1, taken through the insulating chamber and surrounding casing to illustrate the method of securing the insulating chamber in substantially air-tight relation with the chamber;

Figure 4 is a view on an enlarged scale, partly in section and partly in elevation, illustrating one means of securing the electric heater to the bottom of the vulcanizing chamber;

Figure 5 is a similar view illustrating one step in the method followed for securing the heater in position, as shown in Figure 4, consisting in screwing a bolt into the bottom of the vulcanizing chamber;

Figure 6 illustrates the next step which consists in cutting off the bolt flush with the bottom of the vulcanizing chamber;

Figure 7, a third step which consists in screwthreading the portion of the bolt secured in the bottom of the vulcanizing chamber for a portion of its length; and

Figure 8 illustrates a modified means of holding the electric heater against the bottom of the vulcanizing chamber.

Referring to the drawing, the numeral 1 indicates a casing which is preferably of wood and oblong in shape. Mounted in this casing and supported on the upper edges thereof, is a hollow vulcanizing chamber 2 which is adapted to contain water to be heated. This vulcanizing chamber comprises a hollow rectangular vessel open originally on its upper side, and a permanent closure 3 constituting the vulcanizing surface and which also projects beyond the walls of the chamber 2 on all four sides to provide flanges 4 by means of which the vulcanizing chamber is supported on the upper edges of the casing 1 at the sides and ends thereof, as will be apparent from an inspection of Figures 2 and 3. It is a feature of the present invention that the top 3 of the vulcanizing chamber is secured by welding to the upper edges of the chamber 2 and thus becomes substantially integral therewith. Thus not only do I provide for a secure steam-tight closure for the vulcanizing chamber which presents no visible joints or seams but at the same time, as stated, I provide the projecting flanges which serve to support the vulcanizing chamber in the casing 1. On either end of the vulcanizing chamber 2 there is secured, as by welding, riveting or otherwise, a strap 5, these straps being apertured at their lower ends, and after the insulating chamber is in position on the casing, it is pressed down firmly thereon and holes bored in the ends of casing 1 to correspond with apertures in the ends of the straps 5. Thereafter bolts 6 are passed through said bores and apertures to hold the vulcanizing chamber firmly and in substantially air-tight engagement with the top of the casing 1. The manner of securing an electric heater 7 on the bottom of the vulcanizing chamber is another feature of the invention and this will now be described.

In the preferred construction, I first screw a bolt 8 into the bottom 9 of the vulcanizing chamber and wedge the shoulder at the termination of the threaded portion firmly against the said bottom by using great pressure in giving a final turn to the bolt. After this the head and smooth shank portion of the bolt are cut off flush with the bottom 9,

as shown in Figure 6, leaving the threaded portion 10 of the bolt projecting into the vulcanizing chamber. I next provide a screwthreaded aperture 11 in the bolt end 10. 5 The heater 7, in the form I prefer to use, is circular, and to secure it in place, it is provided with a central aperture through which is passed a threaded bolt 12, the end of which engages the bottom of the heater 7 and the 10 screwthreaded portion of which is screwed up into the screwthreaded aperture 11 in bolt end 10. In this way the heater is conveniently and firmly secured in position and at the same time, the bolt end 10 projecting up 15 through the water in the vulcanizing chamber, acts as a heat radiating means and facilitates heating the water in the vulcanizing chamber.

In Figure 8 there is illustrated a modification 20 in the means for supporting the electric heater in contact with the bottom of the vulcanizing chamber and with the bolt end 10. In this arrangement a bail 13, in the form of a flat metal strip bent at right 25 angles to itself, as indicated at 14, at points near its ends, is welded or otherwise secured at its extremities to opposite sides of the vulcanizing chamber 2. The bail 13 has mounted centrally of its length, binding 30 screw 15, the inner end of which is adapted to be screwed into engagement with the under side of the heater 7 and thus hold the same in engagement with the bottom of the vulcanizing chamber, as shown.

35 The parts shown in Figure 1 form no part of the present invention in and of themselves, but to make the subject-matter of the invention clear, they may be briefly described as follows:

40 The numeral 16 indicates a bail which serves as a support for the clamping arms 17 when they are turned out of position, and as a handle by means of which the vulcanizer may be carried, and finally, as a support 45 for a tube when only a small portion of it is clamped on the vulcanizer. The numeral 18 indicates a gage controlled by steam pressure communicated through a pipe 19 from the vulcanizing chamber and which 50 gage is in the circuit of the source of electrical current 20 for the electric heater 7 so that as in my previous application referred to, the heater may be cut off when the pressure of the steam has reached a given 55 amount. The numeral 21 indicates the tube leading from the vulcanizing chamber through the casing and provided with a safety valve 22 for relieving undue pressure of steam generated in the said vulcanizing 60 chamber.

I find that the construction herein illustrated presents the simplest and most economical and efficient arrangement of a vulcanizer of the type shown, of which I have 65 knowledge. The manner of constructing the

vulcanizing chamber by welding the top thereto, which likewise provides flanges for supporting the vulcanizing chamber on the casing, is of decided advantage as not only providing a support, but likewise insuring 70 a hermetically sealed chamber.

The means for holding the electric heater in position, illustrated in Figures 2 to 7, constitute the preferred means for this purpose, as not only does the main holding 75 means, comprising the bolt end 10, also act as a heat radiating member, but the construction provides practically no parts projecting into the casing, the sole exception being the head of the bolt 10, so that the 80 heater can be thoroughly surrounded with heat insulating material, such as asbestos, mineral wool, or the like, as shown, and thus radiation of heat from the heater through the casing be minimized.

I claim:

1. In a vulcanizing apparatus, in combination with a casing, a vulcanizing chamber having a top or cover welded thereon and projecting beyond the body of the vulcanizing chamber to form flanged supports mounted on the upper edge of said casing.

2. In a vulcanizing apparatus, in combination with a casing, a vulcanizing chamber having a top or cover welded thereon and projecting beyond the body of the chamber to afford flanged supports mounted on the upper edge of said casing, and means on said chamber for securing the said flanged supports in firm engagement with the edges of the said casing.

3. In a vulcanizing apparatus, in combination with a casing, a vulcanizing chamber having a top or cover welded thereto and projecting beyond the chamber to provide flanged supports mounted on the upper edge of said casing, straps secured to opposite sides of said chamber and having the free ends provided with bolt holes and bolts passed through the walls of said casing and secured in said bolt holes.

4. In a vulcanizing apparatus, in combination with a vulcanizing chamber, a metal member secured in the bottom thereof provided with a screwthreaded aperture, an electric heater applied to the bottom of said vulcanizing chamber and a screw passed through said heater and into said member for holding the heater in contact with the bottom of the vulcanizing chamber.

5. In a vulcanizing apparatus, in combination with a vulcanizing chamber, a metal member secured in the bottom of the vulcanizing chamber and projecting upward into the interior thereof and provided with a screw-threaded aperture, an electric heater applied to the bottom of the vulcanizing chamber, and a screw passed through said heater and into said metal member for securing the heater in engagement with the 125

under side of the vulcanizing chamber and with said metal member.

6. In a vulcanizing apparatus, in combination with a vulcanizing chamber, a screw-threaded member screwed through the bottom of said chamber to project into the interior of said chamber and having steam-tight connection with said bottom and provided with a longitudinal screwthreaded aperture, an electric heater applied to the bottom of said vulcanizing chamber and to said metal member and a screw passed through said heater having a screwthread shank engaged in said aperture and its head
- 10 in the bottom of said heater to hold the heater in firm engagement with the bottom

of the vulcanizing chamber and with said metal member.

7. In a vulcanizing apparatus, in combination with a vulcanizing chamber, a metal member secured in the bottom of the vulcanizing chamber and projecting upward into the interior thereof, an electric heater applied to the bottom of said vulcanizing chamber at the place of application of said metal member, and means for holding the electric heater in firm engagement with the bottom of said chamber.

In testimony whereof, I have hereunto set my hand.

WILLIAM A. GWYNN.
